UNITED STATES PATENT OFFICE.

FREDERICK A. KOLSTER, OF WASHINGTON, DISTRICT OF COLUMBIA.

RADIO METHOD AND APPARATUS.

1,311,654.

Specification of Letters Patent. Patented July 29, 1919.

Application filed March 31, 1916. Serial No. 87,914.

To all whom it may concern:

Be it known that I, FREDERICK A. KOLSTER, a citizen of the United States, residing at Washington, District of Columbia, have invented a new and useful Radio Method and Apparatus, of which the following is a specification.

My invention relates to radio signaling or control systems involving the transmission through the natural media of electro-radiant energy or electro-magnetic waves for telegraphy, telephony or other signaling or control purposes.

My invention resides in a method of and apparatus for the reception of electro-radiant energy for the purpose of translating the same into signals, messages, or controls with highest efficiency whereby very small electro-radiant energy or electro-radiant energy transmitted from great distances may be so translated; and it is characteristic of my apparatus for this purpose that it is extremely small and compact and may omit features of ordinary receiving apparatus, such as aerial conductor and ground connection.

It is further characteristic of my invention that the electro-radiant energy transmitted from a distant station impinges directly upon and is transformed into high frequency oscillations in a coil or winding constituting inductance of a resonant or tuned circuit, the inductance and capacity of that circuit being concentrated or lumped.

It is further characteristic of my invention that a plurality of such coils may be employed and disposed in such positions that their planes are at an angle with respect to each other and are included in one and the same tuned or resonant circuit or in associated circuits, the coils in some instances being rotatable as a unit to vary the positions of their planes with respect to the direction of the transmitting station, whereby either the direction of that station may be determined with great nicety, or whereby when it is desired to prevent interference by that station or by static electrical effects the static effects or the effects of the station upon the tuned circuit or circuits are completely eliminated, leaving the tuned circuit or circuits to receive undisturbed electro-radiant energy transmitted from a station whose direction is different from that of the first mentioned transmitting station.

My invention resides also in the methods and apparatus hereinafter described and claimed, the foregoing and further characteristics of my invention being determinable from the following description.

For an understanding of my methods and description of some of the forms my apparatus may take, reference is to be had to the accompanying drawings, in which:

Fig. 1 is an elementary perspective view of that form of my invention employing two coils or windings and their relation to a transmitting station.

Fig. 1^a illustrates several forms of cross section of a coil illustrating the close arrangements of the conductors.

Fig. 2 is a diagrammatic view of one arrangement of circuits that may be employed.

Fig. 3 is a diagrammatic view of a modified arrangement of circuits that may be employed.

Fig. 4 is a diagrammatic view of a further modification of circuit arrangements.

Fig. 5 illustrates a further form of apparatus and an arrangement of circuits which may be employed therewith.

Fig. 5^a is a diagrammatic view of a further arrangement involving a double audion.

Fig. 6 is an elevational view of a coil inclosing a capacity area.

Fig. 7 is a diagrammatic view of an arrangement whereby a plurality of apparatus may be employed for determining the direction of a transmitting station, or for preventing interference by such a station when receiving signals or messages or controls from another station.

Fig. 7^a is a diagrammatic view of a modification of the arrangement of Fig. 7.

Fig. 8 is an elementary representation of coils disposed at an angle different from that indicated in some of the prior figures.

Fig. 9 is a diagrammatic view of further modification of circuit arrangements which may be employed.

Referring to Fig. 1, A and B are rectangular coils or windings whose planes are at an angle with respect to each other, 90 degrees in the example illustrated, and which are rotatable about the vertical axis *a*. A pointer or needle *b* rotates with the coils, and with the needle may cooperate the graduated arc or scale *c* which may be stationary or which is at least independent of

- the coils and needle and may itself be movable like a compass card so as to always occupy a given position with respect to the earth's magnetic meridian. The angular extent of the arc *e* may be anything desired and may even reach a complete circumference. *D* and *D'* represent distant stations from each of which is transmitted electro-radiant energy.
- 10 The coils *A* and *B* will preferably each consist of a plurality of convolutions, or turns of wire or conductor, such wires or conductors being arranged closely, or compactly, as indicated in any of the arrangements of Fig. 1^a, or in any other suitable arrangement, the individual conductors being represented by the small circles *d*. By such arrangement the length of each coil is very short as compared with its diameter.
- 15 The conductor *d* may be of any suitable material and is preferably of the now much used litzendraht or high frequency cable. The spacing between the conductors *d* serves to decrease the distributed capacity of the 25 coil.

In Fig. 2 is shown a mode of connection of coils *A* and *B* in circuit. They are, here indicated as connected in series with each other by the conductor *e* and with the adjustable tuning condenser *C*. In a circuit in shunt to the condenser *C* is employed any suitable detector or wave responsive device and an associated indicating instrument such as a telephone receiver now commonly used for reception of signals or messages. In the present example, however, the detector is an audion or like device *E*, which may be used if desired as an oscillating audion for beat reception. It comprises the 30 plate *f* connected to one terminal of the condenser *C* and the grid *g* connected through the variable stop condenser *h* with the other terminal of the variable condenser *C*. The plate *f* and grid *g*, are, as well known, disposed within an evacuated bulb, within which is also disposed a tungsten or other filament *j* adapted to be rendered incandescent by current from the battery *k*. Between the filament *j* and the plate *f* are 35 connected the receiving telephone *T* and the high potential battery *m* whose positive terminal connects with the plate *f* and whose negative terminal connects through the telephone *T* with the filament *j*.

40 It will be noted that there is no aerial conductor employed, nor is a ground connection employed, both of these features being very commonly used in present high power or long distance radio systems.

45 While it shall be understood that it is characteristic of my invention that aerial conductor and earth connections may be dispensed with, and as a matter of fact both or either preferably dispensed with, my invention as to some of its features is not lim-

ited to, the omission of both or either of them.

The coils *A* and *B* are rotated to some position in which energy transmitted from station *D* will produce a response in the telephone receiver *T*. The condenser *C* is adjusted until the circuit including coils *A*, *B* and condenser *C* is sharply in tune or resonant with the energy transmitted from station *D*. The coils are then rotated to such 75 position, as indicated in Fig. 1, that all response by the telephone *T* vanishes, that is, to such position that no signal or response can be heard in the telephone *T*. In that position the effects of the received energy 80 upon the coils *A* and *B* are exactly opposed and neutralized and, if the coils *A* and *B* are similar in all respects, the direction of the station *D* will be indicated by the needle or pointer *b* which exactly bisects the angle between the coils *A* and *B*.

It will be noted that all the inductance of the tuned circuit *A*, *B*, *C* is concentrated in the coils *A*, *B*, and there is no distributed inductance, as in the case where an aerial conductor is employed, or where the conductors connecting the coils to the condenser are long and therefore have substantial distributed inductance, and that, therefore maximum tuning or resonance adjustment of the 90 condenser *C* may be made. In other words, the tuned or resonance circuit approaches very closely to the ideal tuned or resonant circuit, because its distributed inductance is substantially *nil*. And the received electro-radiant energy impinges directly upon the tuned or resonant circuit and not upon an aerial conductor as commonly employed and whose distributed inductance and other characteristics prevent closest approach to 100 ideal conditions for tuning or resonance. While an aerial conductor may absorb a relatively greater amount of electro-radiant energy transmitted from a distant station, yet by my arrangement described wherein 110 less energy is absorbed, the conditions for tuning or resonance are so greatly improved that the difference in the amount of energies absorbed in the two conditions is more than compensated for by the sharpness of 115 tuning and resonance afforded. And such sharpness of tuning or resonance is particularly of importance in direction finding and interference prevention.

120 It is preferred also that in the tuned or resonant circuit *A*, *B*, *C* the ratio of the inductance to the capacity shall be large, for under such circumstances selectivity is correspondingly higher. And making the inductance, large, as compared with the capacity has the further beneficial effect of 125 producing a greater difference of potential between the terminals of the inductance which is particularly desirable when the wave-responsive device is of a potential- 130

operated type as an audion or other electron discharge device.

With apparatus of the character described, the direction of a transmitting station may be determined with extreme nicety and with far greater nicety than by any other method or apparatus of which I am aware.

By way of example merely it may be stated that the direction of a transmitting station, as D, may be determined with an accuracy of less than one degree of arc. That is to say, when the circuit A, B, C has been sharply tuned and the coils A and B rotated in such direction that the response in the telephone T becomes fainter and fainter, such response eventually entirely vanishes, and audible responses are obtained if the coils A and B are rotated in either direction from the true direction of the station D by an amount less than one-half degree of arc.

Assuming that there is a second station D¹ located in a different direction, and that it is desired to receive signals or messages from the station D¹ while the station D is transmitting signals or messages, and that the frequencies of the electro-radiant energies transmitted by these stations are either equal or differ from each other very slightly, interference by station D may be prevented by moving the coils A and B to the position indicated in Fig. 1, in which the needle b points at the station D and there is no response to station D by the telephone T. This will prevent any effect upon the receiving apparatus by the station D, but energy received from the station D¹, since it comes from another direction, will affect the receiving apparatus, and signals from station D¹ will be heard in the telephone T.

And similarly "static" or natural electrical disturbances are prevented from interfering by rotating the coils to that position in which those disturbances produce equal and opposite effects in the coils.

It will be understood that the coils A and B are so wound or connected that when they occupy the position indicated in Fig. 1 the electro-magnetic effect of one is neutralized by that of the other, but that in all other positions the difference in their effects is greater than zero, and signals will be heard in the telephone T. For example, by rotating the coils A and B from the position indicated in Fig. 1 they may be used as an apparatus for receiving signals or messages from station D.

While I have described the employment of two coils, it will be understood that a greater number at various angles may be employed in practising the principle of my invention.

It will be understood that my invention is not limited to the use of a plurality of coils as described but comprehends also the use of

a single coil on which directly impinges the radiant energy and in which substantially all of the energy is received directly from the natural media.

With apparatus of the character above described, the coils A and B may be so small that they may be mounted in an ordinary room. By way of example merely, I may state that with coils A and B each of about 25 turns when connected in series and each approximately eleven feet square, I have received at Washington, D. C., radio signals from a station in Germany, the wave lengths extending over a range of from 5,000 meters to 12,000 meters. The maximum dimension of such a coil, as the diameter or length of a side, is a very small fraction of the wave length of the energy received thereby.

For the detector E in connection with any of the herein described arrangements, I preferably use a potentially operated detector or wave responsive device, though my invention is not limited thereto and may be practised when using a current operated detector or wave responsive device.

In Fig. 3 there is included in circuit with the coils A, B and the adjustable tuning condenser C the primary p, of only one or a very few turns, of an oscillation transformer whose secondary s is adjustable and included in circuit with the adjustable tuning condenser C¹, in shunt to which is connected the circuit of the detector E including the stopping condenser h. A telephone T is suitably associated with the detector. The oscillation transformer may be adjustable as to its co-efficient of coupling.

In Fig. 4 the circuit arrangements are somewhat different from Fig. 2 in that there are present two tuning condensers C² and C³ each having a terminal in common with the common terminals of coils A and B whose remaining terminals connect to the remaining terminals of the condensers C² and C³. One terminal of the detector E is connected to the common terminals of the coils and condensers and its other terminal is connected through stopping condensers h¹ and h², with the remaining terminals of the tuning condensers C² and C³ respectively. Telephone receiver T is suitably associated with the detector E.

In Fig. 5 the coils A and B are indicated diagrammatically, though it will be understood that they may be used in any of the positions and modes described herein or in any other suitable relation. The coil A is shunted by a tuning condenser C² and the coil B by the tuning condenser C³, and, as in Fig. 4, both circuits are tuned to sharp resonance with the received energy.

Within each of the coils, or either of them, may be disposed a capacity area F which may be of any suitable structure, for example, as illustrated, a sheet of metallic gauze,

or any other suitable material. A capacity area and coil are shown on a larger scale in Fig. 6. Each capacity area is connected by a conductor n to one terminal of each of the condensers C^2 and C^3 , whose other terminals have a common connection to earth at o .

The capacity areas F may be used in similar relations with the coils of any other of the herein described arrangements.

- 10 As a detector as utilized in the relation shown in Fig. 5 or in any other of the suitable arrangements herein shown, as for example that of Fig. 4, may be employed a double audion E^1 comprising the filaments j and j^1 connected in series with each other and with their energizing battery k ; the grids g and g^1 connected through the stopping condenser h to the common terminals of the condensers C^2 and C^3 ; and the plates 15 f and f^1 are connected respectively to the other terminals of the condensers C^3 and C^2 and through the high potential batteries m and m^1 and telephone T with the filaments j and j^1 .
- 20 The application of the double audion to the arrangement shown in Fig. 4 is illustrated in Fig. 5^a.

In Fig. 7 is shown an arrangement for any of the purposes herein described, as interference prevention, direction finding, etc., wherein two pairs of rotatable coils are employed and disposed at a distance from each other. With one pair of coils A , B is associated adjustable tuning condenser C , a needle or pointer b and graduated scale c . With the other pair of coils A^1 , B^1 is associated the pointer b^1 and scale c^1 and adjustable tuning condenser C^1 .

From the terminals of condenser C extend 40 the conductors q and r to one set of terminals of the double-throw switch t ; and from the terminals of the condenser C^1 extend the conductors q^1 and r^1 to another pair of terminals of the switch t . Connected to the 45 blades of the switch t are the detector E , of any suitable type, and the stopping condenser h , a telephone T being suitably associated with the detector E .

With the switch t thrown over into communication with conductors q and r the circuit including the condenser C is tuned to the energy transmitted from the station D by varying the condenser C . The coils A and B are then shifted to such position that 55 there is no response in the telephone T , in which case the needle b will point at the station D . Then throwing the switch t over into its other position with conductors q^1 and r^1 the circuit containing condenser C^1 is similarly tuned and the direction of station D found as before, in which case the pointer b^1 will point toward the station D .

We then have a triangle whose sides are x , y and z , the last being the line between 65 the pivotal axes of the two pairs of coils.

The length of side z is known and the two angles between z and x and between z and y have been determined by the positions of the pointers b and b^1 and therefore the direction of the station D is not only accurately 70 known, but its distance is readily computable.

In place of the two condensers C and C^1 there may be employed, provided the conductors q , r and q^1 , r^1 are not long enough 75 to have sufficient distributed inductance to prevent sharp direction finding, a single tuning condenser C with one terminal connected to one blade and the other terminal to the other blade of the switch t , as indicated in Fig. 7^a.

In such case the operator may be located at some point between the two pairs of coils.

The pointers b^2 and b^3 are moved in parallelism with the pointers b and b^1 , respectively, by suitable gearing, belting or other mechanical connections v , v^1 . Or by operating the handles or other remote controlled devices 1 and 2 the two pairs of coils may be rotated from a distance, as from the point 90 where the telephone T is located and the directions found, and in such case the positions of the pointers b and b^1 will be indicated by b^2 and b^3 respectively.

While the angle between the coils has here- 95 inbefore been indicated as 90 degrees, it will be understood that my invention is not limited thereto and that any other suitable angle may be employed. In Fig. 8 the coils A and B are disposed less than 90 degrees 100 between each other with regard to the angle which is bisected by the pointer b .

In Fig. 9 the vertical coils A and B are stationary, that is, are not rotatable. They may be at 90 degrees with respect to each 105 other as indicated, or at any other suitable angle. A stationary coil a^1 has its plane parallel with the plane of a coil A and is connected in series with the coil A and the tuning condenser C . Similarly, there is a 110 stationary coil b^1 connected in series with coil B and the tuning condenser C^1 , the coil b^1 having its plane parallel with the plane of the coil B . c^1 is a coil with its plane vertical and rotatable about the vertical pivotal axis d^1 in inductive relation with the vertical coils a^1 and b^1 . Movable with this coil c^1 is the needle or pointer b^5 cooperating with the scale c . In series with the coil c^1 is the tuning condenser C^2 and in shunt to the latter is a circuit containing the stopping condenser h and detector E , and the telephone T is suitably associated with the detector E .

When the direction of any station is 125 sought, the condensers C , C^1 and C^2 are adjusted so that their respective circuits shall be sharply in resonance for the frequency of the energy transmitted from that station. In this case the coil c^1 only is ro- 130

tated and in that position for which there is no response by telephone T the pointer b^6 will indicate the direction of the station.

The arrangement of Fig. 9 may obviously 5 also be used as an interference preventer by pointing the coil c^1 in the direction of the station whose transmitted signals it is sought to suppress or in the direction of a source of static disturbances, then there will be 10 heard in the telephone T signals from any other station which may be transmitting from some other direction to the exclusion of the first station and static effects.

The condensers h , h^1 and h^2 are employed 15 to prevent flow in the circuits or paths containing them of direct or continuous current or low frequency alternating or fluctuating current, and are known to those skilled in the art as "stop" or "stopping" condensers.

20 In the herein described apparatus the radiant energy impinges directly upon and is directly received in the coil or coils, and substantially all of the energy received is received by the coil or coils directly from 25 the natural media, the associated connections, condenser and in some cases the primary of an oscillation transformer being substantially idle as regards absorption or reception of the radiant energy.

30 What I claim is:

1. The method of translating electro-radiant energy, which consists in absorbing from the natural media substantially the entire received radiant energy directly in 35 a lumped inductance in a path whose distributed inductance is substantially *nil*, attuning the path of the oscillations in said inductance to the frequency of said electro-radiant energy, and translating said oscillations.

2. The method of translating electro-radiant energy, which consists in subjecting an oscillation path or circuit whose distributed inductance is substantially *nil* directly to 45 the electro-radiant energy, attuning said path or circuit to the electro-radiant energy, and translating the resultant oscillations in said path or circuit.

3. The method of translating electro-radiant energy, which consists in absorbing from the natural media substantially the entire received radiant energy directly in a 50 lumped inductance, attuning the path of the oscillations in said inductance to the frequency of said electro-radiant energy, the ratio of inductance to capacity in said path being large, and translating said oscillations.

4. The method of translating electro-radiant energy, which consists in subjecting an oscillation path or circuit whose distributed inductance is substantially *nil* directly to the electro-radiant energy, attuning said path or circuit to said electro-radiant energy by tuning inductance which is 55

large with respect to the tuning capacity, and translating the resultant oscillations.

5. The method of translating electro-radiant energy, which consists in absorbing from the natural media substantially the entire 70 received radiant energy directly in lumped inductances in different planes and in a path or paths whose distributed inductance is substantially *nil*, attuning the path or paths of the resultant oscillations in said inductances 75 to said electro-radiant energy, and translating said oscillations.

6. The method of determining the direction of a source of electro-radiant energy, which consists in absorbing from the natural media 80 substantially the entire radiant energy received from said source directly in lumped inductances disposed in different planes and in a path or paths whose distributed inductance is substantially *nil*, translating said 85 oscillations, and rotating an inductance to a position in which the effect of the translated oscillations attains a maximum or a minimum.

7. The method of determining the direction 90 of a source of electro-radiant energy, which consists in absorbing from the natural media the received radiant energy directly in a path whose distributed inductance is substantially *nil*, attuning said path to the 95 electro-radiant energy, translating the resultant oscillations, and rotating said path until the translated oscillations attain a predetermined value.

8. The method of determining the direction 100 of a source of electro-radiant energy, which consists in absorbing from the natural media substantially the entire received radiant energy directly in an inductance included in an oscillation path whose distributed inductance is substantially *nil*, translating the oscillations resulting in said path, and rotating said inductance to a position in which said oscillations attain a predetermined value. 105

9. The method of determining the direction 110 of a source of electro-radiant energy, which consists in absorbing from the natural media substantially the entire received radiant energy directly in inductances disposed in different planes and included in a path or paths whose distributed inductance is substantially *nil*, attuning said path or paths to the radiant energy, translating the oscillations, and rotating said inductances to a 115 position in which said oscillations attain a predetermined value.

10. The method of preventing interference, which consists in absorbing from the natural media directly in a path whose distributed inductance is substantially *nil* electro-radiant energies from a plurality of sources, attuning said path to the desired radiant energy, rotating said path until the oscillations due to the undesired radiant en- 120

130

ergy are suitably diminished in strength, and translating the oscillations resulting in said path from the desired radiant energy.

11. The method of preventing interference, which consists in absorbing from the natural media directly in an inductance in a path whose distributed inductance is substantially *nil* electro-radiant energies from a plurality of sources, attuning said path to the desired electro-radiant energy, rotating said inductance to a position where the oscillations due to the undesired electro-radiant energy are suitably reduced in strength, and translating the oscillations due to the desired electro-radiant energy.

12. The method of preventing interference, which consists in absorbing from the natural media directly in inductances disposed in different planes electro-radiant energies from a plurality of sources, attuning the path or paths of said inductances to the desired electro-radiant energy, rotating an inductance until the oscillations due to the undesired electro-radiant energy are rendered suitably ineffective, and translating the oscillations due to the desired electro-radiant energy.

13. Apparatus for translating electro-radiant energy comprising a path whose distributed inductance is substantially *nil* absorbing directly from the natural media substantially the entire received radiant energy, and a device responsive to the oscillations set up in said path.

14. Apparatus for translating electro-radiant energy comprising a lumped inductance absorbing directly from the natural media substantially the entire received radiant energy, an oscillation path including said inductance having distributed inductance which is substantially *nil*, means for tuning the oscillation path including said inductance, and a device for translating the absorbed energy.

15. Apparatus for translating electro-radiant energy comprising an inductance absorbing directly from the natural media substantially the entire received radiant energy, capacity for tuning the path of said inductance, the ratio of the inductance to the capacity being large, and a device for translating the absorbed energy.

16. Apparatus for translating electro-radiant energy comprising a path insulated from earth and having practically no distributed inductance absorbing directly from the natural media substantially the entire received radiant energy, means for attuning said path to the received energy, and a device for translating the absorbed energy.

17. Apparatus for translating electro-radiant energy comprising an inductance absorbing directly from the natural media substantially the entire received radiant en-

ergy, the oscillation path including said inductance being insulated from earth and having substantially no distributed inductance, means for attuning said path to the received energy, and a device for translating the received energy.

18. Apparatus for translating electro-radiant energy comprising a closed path rotatable with respect to the direction of propagation of the radiant energy and having substantially no distributed inductance, means for attuning said path to the received energy, and a device for translating the received energy.

19. Apparatus for translating electro-radiant energy comprising a capacity and a rotatable lumped inductance in circuit therewith, said circuit having substantially no distributed inductance and said inductance absorbing directly from the natural media substantially the entire received radiant energy, and a device for translating the received energy.

20. Apparatus for translating electro-radiant energy comprising a path whose distributed inductance is substantially *nil* and including capacity and inductance, said inductance absorbing directly from the natural media substantially the entire received radiant energy, a path in inductive relation to said path, and a device associated with said second path for translating the received energy.

21. Apparatus for translating electro-radiant energy comprising a lumped inductance absorbing directly from the natural media substantially the entire received radiant energy, a capacity associated with said inductance for attuning the oscillation path of the said inductance to the received energy, the distributed inductance of said path being substantially *nil*, a path inductively associated with said first-named path, and a device associated with said second named path for translating the received energy.

22. Apparatus for translating electro-radiant energy comprising a lumped inductance absorbing directly from the natural media substantially the entire received radiant energy, a capacity associated with said inductance for attuning the oscillation path of said inductance to the received energy, the distributed inductance of said path being substantially *nil*, a path inductively associated with said first-named path, means for attuning said second named path, and a device associated with said second named path for translating the received energy.

23. Apparatus for translating electro-radiant energy comprising a lumped inductance absorbing directly from the natural media substantially the entire received radiant energy, a capacity for attuning the

- path including said inductance to the radiant energy, the ratio of the inductance to the capacity being large, a path in inductive relation with said first named path, means 5 for attuning said second named path, and a device associated with said second named path for translating the received energy.
24. Apparatus for translating electro-radiant energy comprising a plurality of 10 closed paths disposed in different planes and having substantially no distributed inductance absorbing the radiant energy directly from the natural media, and means for translating the energy absorbed in said 15 paths.
25. Apparatus for translating electro-radiant energy comprising lumped inductances disposed in different planes in a path or paths whose distributed inductance is 20 substantially *nil* and absorbing the radiant energy directly from the natural media, tuning capacity associated with said inductances, and means for translating the energy absorbed by said inductances.
26. Apparatus for translating electro-radiant energy comprising rotatable lumped inductances disposed in different planes in a path or paths whose distributed inductance is substantially *nil* and absorbing the 30 radiant energy directly from the natural media, tuning capacity associated with said inductances, and means for translating the energy absorbed by said inductances.
27. Apparatus of the character described 35 comprising a resonant circuit including capacity and lumped or concentrated inductance, said inductance being directly subjected to received electro-radiant energy, a capacity area associated with said inductance, and a wave responsive device subjected to the oscillations set up in said circuit.
28. Apparatus of the character described 45 comprising a plurality of concentrated or lumped inductances disposed at an angle with respect to each other and subjected directly to electro-radiant energy, tuning capacity associated with said inductances, a wave responsive device subjected to the resulting oscillations, and a capacity area associated with each of said inductances.
29. Apparatus of the character described 55 comprising a plurality of concentrated or lumped rotatable inductances disposed at an angle with respect to each other and subjected directly to electro-radiant energy, tuning capacity associated with said inductances, a wave responsive device subjected to the resulting oscillations, and a capacity 60 area rotatable with each of said inductances.
30. Apparatus for translating electro-radiant energy comprising a plurality of rotatable inductances disposed in different planes and absorbing directly from the nat- 65 ural media substantially the entire received radiant energy, a tuning condenser in circuit with each of said inductances, and wave-responsive means subjected to the oscillations in the circuits of said inductances, the circuits of said inductances have practically no 70 distributed inductance.
31. Apparatus for translating electro-radiant energy comprising an inductance absorbing radiant energy directly from the natural media, a capacity area inclosed by 75 said inductance, and a device for translating the energy absorbed by said inductance.
32. Apparatus for translating electro-radiant energy comprising a plurality of inductances disposed in different planes and 80 absorbing the radiant energy directly from the natural media, capacity areas inclosed by said inductances, tuning capacity associated with said inductances, and means for translating the energy absorbed by said in- 85 ductances.
33. Apparatus of the character described 90 comprising a plurality of concentrated or lumped inductances disposed at an angle with respect to each other and subjected directly to electro-radiant energy, said inductances connected in series with each other and with a tuning condenser, and a wave responsive device.
34. Apparatus of the character described 95 comprising a plurality of lumped or concentrated inductances disposed at an angle with respect to each other and subjected directly to electro-radiant energy, a tuning condenser and the primary of an oscillation 100 transformer connected in series with said inductances, means for tuning the secondary circuit of said transformer, and a wave responsive device associated with said second- 105 ary circuit.
35. Apparatus for translating electro-radiant energy comprising a circuit or path having substantially no distributed inductance and absorbing the radiant energy directly from the natural media, said circuit or path being rotatable to change its position with respect to the direction of propagation of the radiant energy, and a device 110 for translating the energy absorbed by said circuit or path.
36. Apparatus for translating electro-radiant energy comprising an inductance absorbing directly from the natural media substantially the entire received radiant energy, a tuning condenser, a closed circuit or 120 path having substantially no distributed inductance including said inductance and said condenser, and a device for translating the energy absorbed by said inductance.
37. Apparatus for translating electro-radiant energy comprising a plurality of inductances disposed in different planes and connected in series with each other, tuning 125

capacity associated with said inductances, the ratio of the inductance to the capacity being large, and a potential-operated wave-responsive device for translating the energy absorbed by said inductances.

38. Apparatus for translating electro-radiant energy comprising inductances disposed in different planes, a circuit including said inductances, tuning capacity and the primary of an oscillation transformer, and a wave-responsive device associated with the secondary circuit of said transformer.

39. Apparatus for translating electro-radiant energy comprising an axially short inductance coil absorbing directly from the natural media substantially the entire received radiant energy and consisting of a plurality of turns forming an oscillation path whose distributed inductance is substantially *nil*, and a device for translating the energy absorbed by said inductance coil.

40. Apparatus for translating electro-radiant energy comprising an axially short inductance coil absorbing directly from the natural media substantially the entire received radiant energy and consisting of a plurality of turns of conductor spaced from each other and disposed in a plurality of layers, a tuning condenser, a closed circuit or path having substantially no distributed inductance including said inductance coil and said condenser, and a device for translating the energy absorbed by said inductance coil.

41. Apparatus for translating electro-radiant energy comprising an axially short inductance coil absorbing directly from the natural media substantially the entire received energy and consisting of a plurality of turns, the maximum dimension of said inductance coil being a very small fraction of the wave length of said energy, an oscillation path having substantially no distributed inductance and including said inductance and a tuning condenser, and a device for translating the energy absorbed by said inductance.

42. Apparatus for translating electro-radiant energy comprising a lumped inductance absorbing directly from the natural media substantially the entire received energy and consisting of a plurality of turns of conductor spaced from each other and disposed in a plurality of layers, the maximum dimension of said inductance coil being a very small fraction of the wave length of said energy, and a closed circuit whose distributed inductance is substantially *nil* including said inductance and a tuning condenser, and a device for translating the energy absorbed by said inductance.

43. Receiving apparatus comprising a plurality of rotatable axially short inductance coils disposed at an angle with respect to

each other and each consisting of a plurality of turns of conductor spaced from each other and disposed in a plurality of layers, said inductance coils absorbing directly from the natural media substantially the entire received energy, a path or paths including said inductances and tuning capacity, and oscillation translating means simultaneously subjected to the joint effects of oscillations in said inductances.

44. Receiving apparatus comprising a plurality of lumped inductances disposed at an angle with respect to each other and each consisting of a plurality of turns, said inductances absorbing directly from the natural media substantially the entire received energy, a path or paths whose distributed inductance is substantially *nil* and including said inductances and tuning capacity, and means for translating the received energy.

45. Receiving apparatus comprising a plurality of rotatable lumped inductances disposed at an angle with respect to each other and each consisting of a plurality of turns, said inductances absorbing directly from the natural media substantially the entire received energy, a path or paths whose distributed capacity is substantially *nil* and including said inductances and tuning capacity, and means for translating the received energy.

46. Receiving apparatus comprising a plurality of rotatably lumped inductances disposed at an angle with respect to each other and each consisting of a plurality of turns, said inductances absorbing directly from the natural media substantially the entire received energy, a path or paths including said inductances and tuning capacity, and a translating device simultaneously subjected to the joint effects of oscillations in said inductances.

47. Receiving apparatus comprising a plurality of lumped inductances disposed at an angle with respect to each other and each consisting of a plurality of turns, said inductances absorbing directly from the natural media substantially the entire received energy, a circuit including said inductances connected in series with each other and tuning capacity, and a wave responsive device subjected to the effects produced by the received energy in said inductances.

48. Receiving apparatus comprising a plurality of rotatable lumped inductances disposed at an angle with respect to each other and each consisting of a plurality of turns, said inductances absorbing directly from the natural media substantially the entire received energy, a circuit including said inductances connected in series with each other and tuning capacity, and a wave responsive device subjected to the effects produced by the received energy in said inductances.

49. Receiving apparatus comprising a plu-

rality of lumped inductances disposed at an angle with respect to each other and each consisting of a plurality of turns, said inductances absorbing directly from the natural media substantially the entire received energy, a circuit whose distributed inductance is substantially *nil* including said inductances connected in series with each other and tuning capacity, and a wave responsive device subjected to the effects produced by the received energy in said inductances.

50. Receiving apparatus comprising a plurality of rotatable lumped inductances disposed at an angle with respect to each other and each consisting of a plurality of turns, said inductances absorbing directly from the natural media substantially the entire received energy, a circuit whose distributed inductance is substantially *nil* including said inductances connected in series with each other and tuning capacity, and a wave responsive device subjected to the effects produced by the received energy in said inductances.

51. Receiving apparatus comprising a plurality of rotatable lumped inductances disposed at an angle with respect to each other and each consisting of a plurality of turns, said inductances absorbing directly from the natural media substantially the entire received energy, the maximum dimension of each of said inductances being a very small fraction of the wave length of the radiant energy received thereby, a path or paths including said inductances and tuning capacity, and oscillation translating means simultaneously subjected to the joint effects of oscillations in said inductances.

40 52. Receiving apparatus comprising rotatable lumped inductances disposed at an angle with respect to each other and each consisting of a plurality of turns, said inductances absorbing directly from the natural media substantially the entire received energy, a path or paths including said inductances and tuning capacity, a circuit in inductive relation with said path or paths, and means associated with said circuit for translating the energy received therein.

53. Receiving apparatus comprising rotatable lumped inductances disposed at an angle with respect to each other and each consisting of a plurality of turns, said inductances absorbing directly from the natural media substantially the entire received energy, the maximum dimension of each inductance being a very small fraction of the wave length of the energy received therein, a path or paths including said inductances and tuning capacity, a circuit in

inductive relation with said path or paths, and means for translating the energy received in said circuit.

54. Receiving apparatus comprising a 65 lumped inductance consisting of a plurality of turns, said inductance absorbing directly from the natural media substantially the entire received energy, the maximum dimension of said inductance being a very small 70 fraction of the wave length of the energy received therein, a closed circuit whose distributed inductance is substantially *nil* including said inductance and tuning capacity, a second circuit in inductive relation with 75 said circuit, and means associated with said second circuit for translating the energy received therein.

55. Receiving apparatus comprising a rotatable lumped inductance consisting of a 80 plurality of turns, said inductance absorbing directly from the natural media substantially the entire received energy, the maximum dimension of said inductance being a very small fraction of the wave length 85 of the energy received therein, a closed circuit whose distributed inductance is substantially *nil* including said inductance and tuning capacity, a second circuit in inductive relation with said circuit, and means as 90 sociated with said second circuit for translating the energy received therein.

56. Receiving apparatus comprising inductance coils disposed at an angle with respect to each other and each consisting of a plurality of turns, said inductances absorbing directly from the natural media substantially the entire received energy, the maximum dimension of each inductance being a very small fraction of the wave length 100 of the energy received therein, a path or paths including said inductances and tuning capacity, the ratio of inductance to capacity being large, and a thermionic device subjected to the effects of the energy absorbed 105 by said coils.

57. Apparatus for translating electro-radiant energy comprising an inductance coil absorbing directly from the natural media substantially the entire received radiant energy and consisting of a plurality of turns, a tuning condenser in circuit with said coil, the distributed inductance of the circuit being substantially *nil* and the ratio of inductance to capacity being large, and a 115 thermionic device subjected to the effects of the energy absorbed by said inductance coil.

In testimony whereof I have hereunto affixed my signature this 25th day of March, 1916.

FREDERICK A. KOLSTER.
